UNITED STATES PATENT OFFICE.

RAPHAEL CHARTRAND-MESSNER, OF PORTLAND, OREGON.

GARMENT-SUPPORTER.

1,316,532.

Specification of Letters Patent. Patented Sept. 16, 1919.

Application filed January 22, 1917. Serial No. 143,753.

To all whom it may concern:

Be it known that I, RAPHAEL CHARTRAND-MESSNER, a citizen of the United States, residing at Portland, in the county of

5 Multnomah, State of Oregon, have invented certain new and useful Improvements in Garment-Supporters; and I do hereby declare the following to be a full, clear, and exact description of the invention, such as 10 will enable others skilled in the art to which it appertains to make and use the same.

The present invention is directed to improvements in garment supporters of the suspender type, and has for its object to so

15 construct an article of this type that the same will effectively hold the trousers up through the medium of a pair of buttons, one button being located at each side of the trouser waist band.

20 A further object of the invention is to provide a pair of suspenders so constructed that the same can be used under the shirt so as to hide the suspenders from view when a person is not wearing a vest or coat.

25 A still further object of the invention is to provide a garment supporter having means for supporting the trousers and also the drawers.

With these and other objects in view, this 30 invention resides in the novel features of construction, formation, combination and arrangement of parts to be hereinafter more fully described, claimed and illustrated in the accompanying drawing, in which:—

35 Figure 1 is a view of the supporter showing the position that the parts assume when the same is in use.

Fig. 2 is a sectional view on line 2—2 of Fig. 1.

40 Fig. 3 is a detail perspective view of the combined trouser and drawer supporting device.

Fig. 4 is a sectional view on line 4—4 of Fig. 3.

45 Fig. 5 is a horizontal sectional view through the sleeve.

Referring to the drawing, 1 indicates the single length of strap which may be formed from non-elastic or elastic web, as seen fit.

50 Both ends of the strap 1 are fixed to the loop 2 after the same has been doubled upon itself and passed through the loop 3 carried

by the clamping buckle 4, said buckle being of the conventional form and is adapted to hold the strap in adjusted positions. 55

The strap when in use has portions thereof arranged in intersecting relation which rest upon the back of the wearer, and the loops 5 formed by thus arranging the strap are engaged by the sleeve 6 which is formed by 60 bending a piece of sheet metal 7.

The button loops 8 have their bars 9 engaged in the sleeve 6, likewise the drawer supporting hook 10 has its bars 11 engaged in the sleeve 7, which is in turn engaged in 65 the round or oval sleeve 6.

When the strap is engaged on the body of the wearer the button loops 8 are engaged with the buttons on each side of the inside of the waist band of the trousers, and when 70 it is desired to support the drawers, the usual tapes thereof are engaged in the hooks 10.

The arms of the buttons 8 are provided with depressions 12 which are engaged by the eyes 13 of the brace bar 14, said bar 75 serving to hold the adjacent ends of the bars 9 from spreading.

From the foregoing description it will be seen that a garment supporter has been provided which is so arranged when in use, that the strain on the back of the trousers encountered when wearing the usual suspenders, is eliminated so that the wearer can lean forward without being subjected to the uncomfortable feeling common in the ordinary suspender. 85

What is claimed is:—

A device of the character described including a sleeve around which a portion of a garment supporter is adapted to be engaged, 90 a loop formed of a length of wire having its ends mounted in said sleeve and provided adjacent said sleeve with depressions, a brace bar having its ends mounted in said depressions and connecting the sides of the 95 loops, and a hook also formed of a length of wire having its ends mounted in said sleeve.

In testimony whereof, I affix my signature, in the presence of two witnesses.

RAPHAEL CHARTRAND-MESSNER.

Witnesses:

CLOVIS MESSNER,
J. M. LEEZER.
